UNITED STATES PATENT OFFICE.

KARL EHROTT, OF ERIE, PENNSYLVANIA, ASSIGNOR TO BERNARD GLOEKLER COMPANY, OF PITTSBURGH, PENNSYLVANIA, A CORPORATION OF PENNSYLVANIA.

WAFFLE IRON.

Application filed May 2, 1925. Serial No. 27,428.

My invention relates to waffle-irons.

One object of this invention is to provide novel means for keeping the waffle-irons from overturning when the upper griddle member is swung to its inactive position. Another object is to provide a novel stop for the said member when in the said position. Another object is the provision of a novel pivot-like joint for the electric wires 10 which carry current to the heating element for the said member. I have designed for the said member a novel cover which has a portion overhanging the said joint and the hinges for the said member and which is secured in place by a handle for operating the said member. Another object is to provide troughs along the sides of the lower griddle member, to receive batter exuding 15 between the two members. I have provided 20 a novel electric system whereby visual signals are presented indicating whether the electric system is open or whether the iron is working on a high or a low current value. Other objects appear hereinafter.

25 Referring to the accompanying drawings, Fig. 1 is a side elevation of one form of my invention, with the upper griddle member closed; Fig. 2, a front elevation of the invention; Fig. 3, a plan view of the same, the upper griddle member being open; Fig. 30 4, a section on the line IV—IV on Fig. 3, with the upper griddle member in closed position; Fig. 5, a plan view of the rear portion of the invention with the cover omitted 35 and parts being in section; and Fig. 6, a front view of the waffle-iron with the front removed, parts being broken away; Fig. 7, a section on the line VII—VII on Fig. 5.

40 On the drawings, I show a sheet-metal casing having the downwardly and rearwardly inclined back 1, the sides 2 and 3, the slideable removable bottom 4, and the removable or swinging front 5.

45 The lower griddle member 6, which is preferably made of aluminum, but may be cast-iron, closes the top of the casing and is secured thereto in any suitable manner as by the screws 7 which pass through the casing and into lugs 8 pendent from the member 6.

50 The rectangular batter-heating portion of the griddle 6 is surrounded by the upwardly-extending flange 9. The space enclosed by the flange is divided into four triangular sections by the two partitions 10 and 11

extending diagonally from corner to corner. The four spaces enclosed by the flange 9 and the partitions 10 and 11 are grooved parallel with the partitions whereby numerous rows of flat-topped projections 13 are left terminating at the plane of the top of the flange 9 and the partitions 10 and 11.

55 The upper griddle member 14 has a flange 9' adapted to register with the flange 9 when the member 14 is placed in baking position 60 on the member 6. The member 14 has partitions 10' and 11' and projections 13' arranged to register respectively with the partitions 10 and 11 and projections 13 when the flanges 9 and 9' are registered with each 65 other. The rear edges of the members 6 and 14 are provided respectively with the hinge-lugs 15 and 16, which are pivoted together by the hinge-pins or screws 17.

70 The upper face of the griddle member 14 75 is provided with the annular electric resistor or heating member 18 surrounding the boss 19 on the said member. A sheet-metal plate 20 overlies the resistor 18 and is held in place by the screw 21 passed through the plate and 80 into the boss.

75 The lower face of the griddle member 6 is provided with the resistor 18' held in place by the plate 20' by the retaining screw 21' which is passed into the member 6. 85

80 The upper face of the griddle member 14 has the upstanding flange 22 rising above the plate 20. Resting on the member 14 is the cover 23 made preferably of aluminum and having the flange 24 registering with 90 the flange 22. The cover extends rearwardly to form the extension 25 which lies over the hinge-joints and curves downwardly for a distance behind them. The cover has at its 95 sides the lugs 26 which overlap the inner face of the flange 22 to which they are secured by the screws 27. The cover has also the lug 28 overlapping the inner face of the flange 22. The handle 29 for operating the member 14 has at one end the 100 screw 30 which passes through the flange 22 and into the lug 28, so that the handle not only operates the member 14 but also holds the cover 23 thereon.

105 The member 6 has the external horizontal flange 31 enclosing at least three sides of the member 6. The upper face of the flange 31 preferably has the trough 32 to receive the batter exuding from between the griddle members. The exuded batter can be readily 110

removed with a knife or other tool. The flange prevents the batter from running down the sides of the casing and dropping upon the waffle-iron support or floor.

5 The rear edge 33 of the cover extension engages the lugs 34 on the hinge-lugs 15 when the upper griddle member 14 is swung upwardly and backwardly to its limit, as shown in Fig. 3. At this time considerable 10 weight is transferred from a position in front of the hinge-pins 17, where the member 14 rests directly upon the member 6, to a position at the rear of the hinge-pins. This transfer of weight produces a force 15 tending to overturn the entire apparatus toward the rear. This tendency is counteracted by the projection of the base of the back 1 considerably to the rear of the said pivot-pins, so that the center of gravity of 20 the apparatus is in front of the bottom edge of the back 1.

35 is an electric control switch and 36 and 37 are two electric lamps, one at each side of the switch. The front 5 has the openings 38 and 39 through which the lamps may be seen. 25 48, 49, 50, and 51 shown in Fig. 6 are electric wires connected to the lamps 36 and 37.

All the wiring system is beneath the lower griddle member 6 except the resistor 30 18, to which are connected the supply wires 45 and 58. The wires 45 and 58 pass out through the rear edge of the griddle member 6 and thence through the hollow L-shaped member 59, thence through the hollow L-shaped member 60, and into the rear 35 edge of the griddle member 14. The outer open ends of the members 59 and 60 face each other, the member 59 having in its end the circular recess 61 which receives the annular projection 62 on the end of the member 60. The axial centers of the pivot pins 17 and the described pivot-like joint between the members 59 and 60 are in a straight line, 40

so that when the griddle member 14 is oscillated, the projection 62 turns in the recess 61 45 without binding.

On Fig. 5, it is shown that the distance between the hinge-lugs 16 is greater than the distance between the outer faces of the hinge-lugs 15, the difference between these 50 distances being at least equal to the length of the projection 62. In assembling the griddle member 14 with the griddle member 6, the hinge-lugs are arranged with the lugs 15 between the lugs 16, but the hinge-lug 15 55 which is on the opposite side of the member 59 from the projection 62 is first placed close to the adjacent hinge-lug 16. Then the griddle member 14 is slid so as to cause the projection 62 to enter the recess 61. Then 60 the hinge pins 17 are inserted through the lugs 16 and screwed into the lugs 15, but before the pin nearest the lower part of Fig. 5 is inserted a washer 63 is placed between the lower hinge members 15 and 16, the washer 65 being as thick as the projection 62 is long. The latter hinge pin extends through the hole in the washer, which prevents lateral movement of the upper griddle member.

I claim:—

In a waffle-iron, a lower griddle member, an upper griddle member hinged thereto, a cover lying on the upper member, means depending from the cover back from the front edges of the cover and the upper member 75 and lapping the upper member a short distance back from its front face, a handle wholly external of the cover, and means cooperating with the handle, the said depending means and the upper griddle member 80 for securing the handle, the cover and the upper griddle member rigidly together.

Signed at Pittsburgh, Pa., this 18th day of April, 1925.

KARL EHRGOTT.
